Patented May 12, 1959

185,177

GOLF CLUB HEAD

Kenneth Smith, Lenexa, Kans.

Application December 27, 1955, Serial No. 39,478

Term of patent 14 years

(Cl. D34—5)

Fig. 1 is a top front view of the golf club head, showing my new design;

Fig. 2 is a face view thereof;

Fig. 3 is a toe end view thereof;

Fig. 4 is a fragmentary rear elevational view thereof;
and

Fig. 5 is a bottom view of the golf club head.

I claim:

The ornamental design for a golf club head, as shown.
